International Preliminary Report on Patentability for Int. App. No. PCT/US2012/037933, mailed Jan. 23, 2014.

Primary Examiner — David Muller(74) *Attorney, Agent, or Firm* — McDonnell Boehnen Hulbert & Berghoff LLP(57) **CLAIM**

The ornamental design for a flange extender, as shown and described.

DESCRIPTION

FIG. 1 is a first embodiment of a flange extender in a perspective view;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the drawings that form no part of the claimed design.
